UNITED STATES PATENT OFFICE.

ULYSSES E. LUDWICK, OF OMAHA, NEBRASKA.

ENGINE.

1,053,414.

Specification of Letters Patent. Patented Feb. 18, 1913.

Application filed March 9, 1912. Serial No. 682,735.

To all whom it may concern:

Be it known that I, ULYSSES E. LUDWICK, a citizen of the United States, residing at Omaha, in the county of Douglas and State 5 of Nebraska, have invented certain new and useful Improvements in Engines, of which the following is a specification.

This invention relates to improvements in engines, and while the construction could be 10 employed to advantage in connection with the force of steam, or similar expansion element, as a motive power, it is illustrated and described herein as a gasolene engine, and has for its object to provide a construction 15 whereby the pistons within the cylinders may be reciprocated simultaneously by a single impulse of the expansive force employed, said force being delivered in alternation at or upon the opposite ends of the 20 pistons, thereby producing a required operation by use of a less number of parts than ordinary.

The invention consists of the novel construction, combination and arrangement of 25 parts as described herein and claimed and as illustrated in the drawing, it being understood that changes in form, size, proportion and minor details may be made within the scope of the claims without departing from 30 the spirit of the invention or sacrificing any of its advantages.

In the drawing, Figure 1 is a plan view of the engine. Fig. 2 is a detail, in section, of the check valve. Fig. 3 is a side elevation 35 of the engine, parts of the cylinders and frame being broken away. Fig. 4 is a vertical section on line *a a* of Fig. 3. Fig. 5 is a view in longitudinal section through the frame, rotatable disk and cylinders, as on 40 line *b b* of Fig. 1. Fig. 6 is a view showing the inner side of one of the housing-plates. Fig. 7 is a side view of the disk. Fig. 8 is a partly broken, edgewise view of the disk.

Referring now to the drawing for a more 45 particular description, numeral 1 indicates the engine shaft having bearings in the pair of upright casings or frame-members 2, the shaft being provided with oppositely-disposed cranks 3, and a balance wheel 4. Se- 50 cured upon members 2 are upright, adjacent cylinders 5 and 6, hereinafter referred to, for convenience, as first and second cylinders, respectively, each of the cylinders be- 55 ing provided with a piston 7, and a piston-

rod 8 connects each piston with one of 55 cranks 3.

At 9 and 10 are indicated housing plates, each being formed with a depressed middle part or circular recess 11, the flat, vertical wall of each recess being provided with a 60 central aperture 12. The housing plates are adapted to be disposed in contact, side-by-side, between the cylinders, their recesses 11 forming a circular chamber 13 (Fig. 4); and they may be provided with curved 65 arms 14 for engaging the walls of the cylinders, the arms being secured together by keepers 15.

At 16 is indicated a casting, cylindrical valve member, or disk provided upon its 70 opposite sides at its middle with projections, bosses or trunnions 17 (Fig. 8). The disk is adapted to have a seating in the circular chamber 13, its bosses 17 having bearings 75 in apertures 12 of the housing plates. Each of the bosses 17 is provided with an aperture 18 (Figs. 4, 7 and 8), said aperture also extending through the middle of the disk. The disk is also formed with a straight passageway 19 extending radially therethrough, 80 and in communication with aperture 18, and said passageway 19 provides an explosion chamber with two discharge-ports 20 and 21 diametrically opposite to each other opening 85 upon the periphery of the disk.

Passageways 22 and 23 are formed between the housing plates. These passageways communicate with and at diametrically opposite sides of the circular chamber 13, and with the respective upper and 90 lower ends of the cylinders. Said passageways may be formed as grooves in the inner sides of the housing plates, and when the plates are secured side-by-side the grooves 95 will register with each other in a manner to form the complete passageways, the housing plates being secured together and in contact by keepers 24.

The disk is provided with exhaust or discharge passageways 25 and 26, each having 100 a port 27 and a second port 28 opening upon the periphery of the disk, substantially 60 degrees from a port 20 or a port 21 thereof.

Discharge pipes 29 are provided; they are mounted upon and extend outwardly from 105 the side of the housing plate 10 (Fig. 1), and as plainly shown in Fig. 6 apertures 30 are formed in the wall of housing plate 10

to communicate with these discharge pipes, also by reference to Figs. 5 and 6 it will be seen that comparatively short grooves 31 are formed in each housing plate to communicate with the apertures 30 and with the circular chamber 13.

Grooves 31, for convenience, may be designated as intermediate grooves, since they are each disposed between passageways 22 10 and 23 at points substantially 60 degrees from said passageways; and when the housing plates are secured together as above mentioned, each pair of grooves 31 will register with each other to form comparatively short 15 passageways opening upon chamber 13 at points diametrically opposite to each other, and communicating with discharge pipes 29.

Passageways 22 and 23 are alike in form and all of the functions discharged by one 20 are discharged by the other. Passageway 22 may be designated as forward ports and passageway 23 the rearward ports of the cylinders. Passageways 22 provide exhaust passages for the cylinders when the pistons move forwardly; and passageway 23 operate as exhaust passages for the cylinders when the pistons move rearwardly.

Means are provided and will presently be described for causing a part rotation of the 30 disk first in one direction and then in a reverse direction, this rotatable movement of the disk being substantially 60 degrees.

By referring to Fig. 5 it will be seen that ports 20 and 21 of the explosion chamber 35 19 may have simultaneous communication, respectively, with the passageway 22 leading to the upper end of cylinder 5, and with the passageway 23 leading to the lower end of cylinder 6, and at this time if gas be exploded within chamber 19, pistons 7 may be moved toward the ends of the cylinders opposite to the ends which they occupied, to cause one-half of a complete rotation of the engine shaft.

45 At 32, mounted in aperture 18 of the disk, is indicated a spark-plug for causing intermittent discharges of fuel gas. The gas, under pressure, may pass within aperture 18 and chamber 19 from feed pipe 33 50 (Figs. 1, 4.) by first passing through check-valve 34, said valve preventing a return or outward movement of the charges of gas after passing within said chamber 19.

Any suitable means may be provided to 55 cause a reciprocatory rotative movement of the disk, the means herein shown being the rod 35. The upper end of this rod is pivotally mounted upon the pivot-pin 36 (Figs. 7, 8.) which projects transversely from one 60 of the sides of the disk near one of bosses 17, said pin traversing the slot 37 formed in housing-plate 10. The lower end of rod 35 is pivotally mounted upon rock lever 38, said lever having a pivotal mounting at 65 39 upon the supporting-plate or bracket 40 se-

cured upon one of frame-members 2. The free end of lever 38 is disposed adjacent to a piston rod 8; upon this piston rod a pair of adjacent contact-rings 41 and 42 may be loosely or slidably disposed. At 47 is indicated a boss or collar which is rigidly secured to this piston-rod, the guide of the piston-rod being indicated at 48. Coiled springs 49 and 50 of equal length may be employed and mounted upon said piston-rod, spring 49 being disposed between and bearing upon collar 47 and contact-ring 41, and spring 50 being disposed between and bearing upon contact-ring 42 and guide 48.

The parts are so arranged that when the piston within cylinder 5 has moved upwardly a part of its stroke, the free end of lever 38 will be engaged by contact-ring 42, and the free end of said lever will be moved upwardly to cause rod 35 to pass downwardly, said downward movement of rod 35 causing a part rotation of the disk, this rotative movement being 60 degrees. Springs 49 and 50 are constructed of such a strength that they will not be compressed by the contact of rings 41 and 42 with the free end of the rock-lever to effect said rotative movement of the disk 60 degrees. At the time of the downward movement of rod 35, pin 36, of course, will move downwardly within and will have a bearing upon the lower end of slot 37 of housing-plate 10, and this slot is of a suitable length to prevent the disk from rotating in an arc of more than 60 degrees. During the movements of the piston within cylinder 5, contact-rings 41 and 42 will be engaged, in alternation, by the free end of the rock-lever. The disk will be moved in an arc of 60 degrees at each movement of the piston, and springs 49 and 50 will be compressed, in alternation, while the piston is completing its strokes. The compression of springs 49 and 50 therefore occurs after the free end of lever 38 has engaged these respective contact-rings and only after the disk has been moved; and the completion of strokes of the cylinders, after contact-rings 41 and 42 have been engaged by the free end of the rock-lever, causes the fuel gas within the cylinders to be compressed, these intermittent compressions of the gas occurring immediately before the charges are exploded.

In order that it may be clearly understood that the movable disk provides exit ways for the escape of decomposed fuel gas from the cylinders, and provides intakes for the charges of fuel gas, so that the force of the explosions may be directed, in alternation, at both ends of the pistons, operation of these parts will now be described.

During the intervals between its rotative movements of 60 degrees above mentioned, the disk will remain in a condition of rest,

being under control of rod 35; and rod 35 is caused to remain stationary at all times except when lever 38 is moved by contact-rings 41 and 42, this being effected by the segmental friction block 43 of rock lever 38.

At 44 are indicated pivotally mounted pawls or lugs adapted to bear frictionally upon the surface of block 43 by reason of springs 45, the pressure or force of said springs 45 being sufficient to prevent any movement of rod 35 except when contact-rings 41 or 42 move into engagement with lever 38.

In operation, gas under pressure will overcome the force of spring 46 of valve 34 (Fig. 2), and this spring being compressed, the gas will enter aperture 18 and passageway or explosion chamber 19. When in a position of rest, the ports 20 and 21 are always in communication with a passageway 22 and 23 diametrically opposite to each other and which lead to the lower end of one and the upper end of the other cylinder. Assuming the parts to be in the relative positions shown in Fig. 3, the gas when exploded would cause a simultaneous movement of the pistons to cause one-half of a revolution of the engine shaft, the piston of cylinder 5 moving upwardly, the piston of cylinder 6 moving downwardly, the ports 20 and 21 of chamber 19, at the time of the explosion, being in communication, respectively, with the upper passageway 22 which communicates with the upper end of cylinder 6, and with the lower passageway 23 which communicates with the lower end of cylinder 5. During the simultaneous movement of the pistons last described it will be understood that the disk will remain in a position of rest until the piston within cylinder 5 has completed a part of its upward or forward movement within said cylinder, and therefore, during a part of this movement of said piston, any foul air within said cylinder 5 will be forced out through the passageway 22 which communicates therewith, and the foul air will pass through passageway 26 of the disk, since port 27 of passageway 26 will be in communication with the passageway 22 of said cylinder 5. Likewise, during this movement of the pistons, the foul air within cylinder 6 will be forced out through passageway 23 at the rear part of this cylinder, and will pass through passageway 25 of the disk, since port 28 of passageway 25 will be in communication with said passageway 23 of cylinder 6 and with passageway 31 adjacent to cylinder 6. Passageways 25 and 26 of the disk therefore operate as channels through which the exhausted fuel gas may escape from the cylinders, and from passageways 22 and 23.

In operation, when the pistons within cylinders 5 and 6 arrive near to the ends of

said cylinders as shown in Fig. 5, the foul air or the greater part of it will have passed out of the discharge pipes 29; and at this time, the strokes of the pistons being complete, the explosion occurs within chamber 19 to cause the pistons to move to the positions shown in Fig. 3; and the adjustment of parts is such that when the rearward movement of the piston within cylinder 5 has been partly completed, rod 35, before spring 49 has been compressed, will be moved upwardly or forwardly to the position shown in Fig. 3, the disk being partly rotated and disposed in the position shown in Fig. 3; and the disk will thereafter remain in the position shown in Fig. 3 until the contact-ring 42 has been engaged by the free end of the rock-lever. The disk is therefore disposed stationary while the pistons are moving, except at the instant when one of the contact-rings engage the rock-lever, and the foul air may escape from the cylinders while the disk is stationary; and on account of the construction, the charges or explosions are delivered in alternation within the cylinders upon opposite ends of the piston, the movements of the piston being simultaneous to cause, at each of said movements, one-half of a rotatable movement of the engine shaft. As thus described, passageways 20 and 23 may be considered intakes or exit ways for the cylinders, according to the direction of movement of the pistons therebetween. When chamber 19 is in communication with one of passageways 22 and 23, the other passageways 22 and 23, of course, operate as exit ways for the exhaust or passage of foul air from the cylinders.

Having fully described the several parts and their uses, a further explanation relating to operation is not necessary.

What I claim as my invention and desire to secure by Letters Patent is,—

1. An engine, comprising, in combination with a pair of cylinders each having a port at each of its terminals, and a piston disposed between said ports; a member having an explosion chamber and a pair of discharge passages, said member being movable to dispose its explosion chamber in communication with one of the terminal ports of each cylinder, its discharge passages communicating with the other terminal ports of the cylinders.

2. An engine, comprising, in combination with a pair of cylinders each having a port at each of its terminals, and a piston disposed between said ports; a disk having an explosion chamber opening at diametrically opposite parts of its periphery and provided with a pair of discharge passages, said disk being movable to dispose its explosion chamber in communication with one of the terminal ports of each cylinder, its

discharge passages communicating with the other terminal ports of the cylinders.

3. An engine comprising, in combination with a pair of cylinders each having a port at each of its terminals, and a piston disposed between said ports; a member having an explosion chamber and a pair of discharge passages, said member being movable to dispose its explosion chamber in communication, in alternation, with the terminal ports of the cylinders, its discharge passages communicating, in alternation, with the terminal ports of one of said cylinders.

4. An engine, comprising, in combination with a pair of cylinders each having a port at each of its terminals, and a piston disposed between said ports; a disk having an explosion chamber opening at diametrically opposite parts of its periphery and provided with a pair of discharge passages, said disk being movable to dispose its explosion chamber in communication, in alternation, with the terminal ports of the cylinders, each of its discharge passages communicating, in alternation, with the terminal ports of one of said cylinders.

5. An engine, comprising, in combination with a pair of cylinders each having a port at each of its terminals, and a piston disposed between said ports; a disk having an explosion chamber with ports opening opposite to each other upon its periphery, and having passages with ports opening

upon its periphery intermediate the ports of the explosion chamber; said disk being adapted to have a reciprocatory rotative movement in an arc of substantially sixty degrees to dispose the ports of its explosion chamber in communication, in alternation, with the terminal ports of the cylinders, each of the ports of its discharge passages communicating, in alternation, with the terminal ports of one of said cylinders.

6. An engine, comprising, in combination with a pair of cylinders, each having a port at each of its terminals and a piston disposed between said ports; a pivotally mounted disk having an explosion chamber and a pair of discharge passages, said disk being movable to dispose its explosion chamber in communication with one of the terminal ports of each cylinder to cause a simultaneous longitudinal movement of the pistons, the operation being that the disk will remain in a position of rest with its discharge passages in communication with one of the terminal ports of each cylinder until the pistons have completed a part of their longitudinal movements.

In testimony whereof I have affixed my signature in presence of two witnesses.

ULYSSES E. LUDWICK.
